FRANK LA OTIS LATHROP, OF WALLINGFORD, CONNECTICUT, ASSIGNOR TO H. L. JUDD COMPANY, OF WALLINGFORD, CONNECTICUT, A CORPORATION OF NEW YORK.

CURTAIN ROD AND BRACKET.

1,044,893.

Specification of Letters Patent. Patented Nov. 19, 1912.

Application filed May 24, 1912. Serial No. 699,362.

To all whom it may concern:

Be it known that I, FRANK LA OTIS LATHROP, a citizen of the United States, residing at Wallingford, New Haven county, 5 State of Connecticut, have invented certain new and useful Improvements in Curtain Rods and Brackets, of which the following is a full, clear, and exact description.

This invention relates to curtain supports, 10 and particularly to a coöperating rod and bracket construction therefor.

In its broad aspect, it contemplates the use of a wall bracket slotted to receive the end of the curtain rod and carrying a keeper 15 adapted to maintain the end of the rod in engagement with the bracket.

The preferable embodiment of the invention is illustrated in the accompanying drawings, in which—

20 Figure 1 is a top plan view of a curtain rod and its brackets, constructed in accordance with the present invention. Fig. 2 is a front elevation of the parts shown in Fig. 1. Fig. 3 is a vertical sectional view, partly 25 in elevation, of a rod end and supporting bracket, such as shown in Figs. 1 and 2, but on an enlarged scale. Fig. 4 is a front elevation of a bracket with the rod detached therefrom.

30 Referring to the drawings by numerals: 1 indicates a curtain rod of the tubular telescopic type having inwardly bent ends provided with the tip members 2.

35 3 indicates the supporting brackets for the curtain rod, these brackets comprising face plates 3^a provided with side flanges or walls 4 serving to space the face plates from the wall or molding to which the brackets are secured.

40 As the construction of each of the brackets and rod tips is the same, a description of one in detail will suffice for both. The face plate of the bracket is formed with a key-hole slot 5, the material of the face plate 45 being punched out to form this slot and being bent backwardly and rearwardly from the slotted portion to form a spring tongue or keeper 6, the lower end of which is provided with a locking protuberance 7, the

function of which will appear hereafter. 50 The rod tip 2 adjacent its end is provided with an annular recess 8 of sufficient depth to make the diameter of the tip at this point less than the width of the narrowed portion of the key-hole slot 5. This, therefore, provides the tip end with two annular abutment shoulders 9 and 10. The end of the tip is apertured as at 9^a, this aperture being preferably of a diameter approximating that of the protuberance 7 at the end of the 55 spring keeper 6. With this construction of the parts in mind, the coöperating use of the rods and brackets will be seen to be as follows: Assuming that the telescopic rods and their brackets have been adjusted to the 60 desired width of curtain, the brackets are then secured to the wall molding or other suitable support by means of the screws shown, their side flanges or walls 4 spacing the face plates from the wall and allowing 65 sufficient free play on the part of the spring keeper 6. The ends of the rods are then positioned to bring their tips in alinement with and through the upper enlarged end of the key-hole-slots 5. The operator then moves 70 the ends of the rods inwardly against the pressure of the spring keepers 6 and moves them downwardly to bring the annular recesses 8 in line with the edges of the face plate adjacent the narrowed portion of the 75 slot. This will cause the annular shoulders 9—10 on either side of the recesses 8 to abut against the interior and exterior of the face plates of the brackets, and when the rod ends have been brought to the lower extremity of the key-hole slots, the protuberances 80 7 at the ends of the spring tongues 6 will snap into the apertures 9^a formed in the ends of the rod tips 2 and thereby maintain the curtain rod in engagement with its 85 brackets and detachably lock its ends against withdrawal. The annular shoulders 9 will be pressed against the interior of the face plates of the brackets by the spring keepers and will be frictionally held in engagement therewith and locked against accidental withdrawal by the spring keepers 6 and their locking protuberances 7. The an-

nular shoulders 10 abutting against the exterior of the face plates will prevent inward movement of the ends of the rods, these two shoulders, therefore, coöperating to afford a firm support for the curtain rod and the hanging mounted thereon.

It will be noted that I have formed the brackets from a single piece of sheet metal, the spring keeper being formed integrally therewith by utilizing the material stamped out from the face plates of the brackets in forming the key-hole slot therein. It should also be noted that the protuberances formed at the lower ends of the spring keepers 6, are rounded so that the ends of the curtain rods may be moved upwardly in the key-hole slots of their brackets, the inner faces of the rod tips riding over these end protuberances and moving the spring keepers rearwardly to permit the withdrawal of the curtain rods from the brackets.

While I have described and shown herein a specific embodiment of the invention, I desire it understood that various modifications in the structure thereof are possible within the spirit of the invention and within the scope of the appended claims.

What I claim, therefore, and desire to secure by Letters Patent is:

30 1. In a device of the character described, in combination, a wall bracket having a face plate spaced from the wall and provided with a slot therein, a spring keeper carried by said bracket in rear of said slot, and a 35 curtain rod having its end adapted to be inserted through said slot to engage and be detachably interlocked with said keeper.

2. In a device of the character described, in combination, a wall bracket having a face 40 plate spaced from the wall and provided with a key-hole slot therein intermediate its edges, a spring keeper carried by said bracket in rear of said slot, and a curtain rod having a shouldered end adapted to be 45 inserted through said slot to engage said spring keeper and be held thereby with its shoulder in engagement with said bracket.

3. In a device of the character described, in combination, a wall bracket spaced from 50 the wall and having a slot therein, a curtain rod having a shouldered abutment end adapted to be inserted within said bracket slot and to abut against said bracket, and a spring keeper carried within said bracket in 55 alignment with said slot, said keeper being provided with a protuberance and said abutment end being provided with an aperture adapted to be engaged by said protuberance whereby said abutment end is detachably 60 locked in engagement with said bracket.

4. In a device of the character described, in combination, a wall bracket having a face plate spaced from the wall and provided with a key-hole slot therein, a spring keeper

carried by said bracket in rear of said slot, 65 and a curtain rod having a shouldered end adapted to be inserted through said slot to engage said spring keeper and be held thereby with its shoulder in engagement with said bracket and with its end detachably interlocked with said keeper.

5: In a device of the character described, in combination, a wall bracket comprising a face plate and side flanges adapted to engage the wall and space said face plate therefrom, a key-hole slot in said face plate, a curtain rod having a shouldered abutment end adapted to be inserted through said key-hole slot, and a spring keeper carried within said bracket and in alignment with said slot and positioned to engage said abutment end to maintain it in engagement with said face plate, said abutment end being apertured and said keeper plate being provided with an aligned protuberance adapted to seat 85 in said abutment aperture and detachably lock said abutment end in engagement with said bracket.

6. In a device of the character described, in combination, a wall bracket comprising a face plate and side flanges adapted to engage the wall and space said face plate therefrom, a key-hole slot in said face plate, a curtain rod end having an annular recess therein and adapted to be inserted through 95 said bracket slot with its annular recessed portion between the narrowed walls thereof and with the faces of the rod end adjacent said recessed portion abutting the exterior and interior of the face plate of said bracket, 100 and a spring keeper carried by said bracket within said face plate and in alignment with said slot and positioned to engage said rod end and maintain it in engagement with the face plate of said bracket.

7. In a device of the character described, in combination, a wall bracket comprising a face plate and side flanges adapted to engage the wall and space said face plate therefrom, a key-hole slot in said face plate, 110 a curtain rod end having an annular recess therein and adapted to be inserted through said bracket slot with its annular recessed portion between the narrowed walls thereof and with the faces of the rod end adjacent 115 said recessed portion abutting the exterior and interior of the face plate of said bracket, and a spring keeper carried by said bracket within said face plate and in alignment with said slot and positioned to engage said rod end, said spring keeper being provided with a protuberance and said rod end with an aligned aperture whereby said rod is maintained in 120 engagement with the face plate of said bracket and is detachably locked in such position.

8. In a device of the character described, in combination, a wall bracket having a face

plate spaced from the wall and provided with an integral spring keeper struck inwardly therefrom to form a slot in said face plate, and a curtain rod end provided with 5 spaced abutments and adapted to be inserted within said slot to engage said keeper and be maintained thereby in engagement with said face plate with said abutments positioned on either side thereof.
